MANUALLY OPERATED FIELD LINE INSULATOR

Harold L. Boerlin, Alexandria, Va.

Application September 16, 1953, Serial No. 380,629

5 Claims. (Cl. 174—154)

(Granted under Title 35, U. S. Code (1952), sec. 266)

The invention described herein may be manufactured and used by or for the Government of the United States for governmental purposes without the payment to me or my legal successors of any royalty thereon.

This invention relates to insulators constructed for rapid emplacement and removal of telegraph and telephone lines especially, although it may be applied to use in supporting other electrical conductor lines, as will be understood from the following disclosure.

The invention is especially important to the armed services, where exigencies of battle conditions may require extreme haste in hanging or removal of lines of communication.

It is therefore an important aim of the invention to present a construction adapted to be produced at reasonable cost which will enable instant stringing of communication lines by simple manual operation of an inclosing insulator.

The invention is particularly useful as a pendant cross arm bracket which may be mounted temporarily or permanently on the cross arm, and will enable placement and securement of a conductor by a lineman standing on the ground therebelow. Quick-mounting means for securing such an insulator to a cross arm are available and may be substituted where found desirable as, for instance, shown at Figures 4 and 5. Other mounting expedients are found in patent to Fleener, 2,235,108, March 18, 1941, and patent to Cook, 1,090,686, March 17, 1944.

A further aim of the invention is to enable the production of an extremely rugged insulator assembly liable in a minimum degree to injury or derangement in the severe usage to which material is subjected in military use and particularly in battle conditions, while at the same time attaining the object of quick wire suspension and manual fastening and release.

Objects, advantages and features of invention in addition to those indicated above reside in the construction, arrangement and combination of parts involved in the embodiment of the invention, as will be indicated or understood by or from the accompanying description and drawings, wherein

Fig. 1 is an elevation of one embodiment of the invention substantially twice the actual size required for a conductor of substantial size, although the proportions of the device may be greater or less, according to the requirements of the service and the nature of the line to be supported;

Fig. 2 is an elevational view of the blank for the shank and strap of the invention as viewed from the left of Fig. 1, substantial parts of the device being broken away to reduce the length of the illustration;

Fig. 3 is a top view of the appliance unmounted, as shown in Fig. 1;

Fig. 4 is an elevation of a modified hanger device attachable to a cross arm without use of any tool, or possibly the use of a hammer, initially positioned on the cross arm for movement to secured position;

2

Fig. 5 is a similar view showing the hanger in final position on the cross arm.

Referring to the drawings more particularly, there is illustrated a portion of a wooden cross arm 10, of conventional construction upon which my insulator is suspended. The insulator is a bracket device comprising a hanger body 11 formed from stock circular round steel rod, although other materials may be used as found preferable. The upper part of the body consists of a shank 10 having a threaded extremity which is inserted through a cross arm, a washer 12 being held against the lower side of the cross arm by struck lugs 13 formed on the side of the shank, and the shank is secured by means of a conventional nut and washer on the extremity of the shank at 15 14 engaged against the upper side of the cross arm.

The lower part of the shank is rolled on one side to form an intermediate rigid shank or main bracket arm portion 16, rectangular in cross section, one broad side being aligned with one side of the upper shank as in Fig. 20 1, and the lower end of the body is further rolled to form a thinner broad strap portion 17 which is bent upward and formed to a substantially U shape or hook-like form, open upward beside the shank 15 and with its bight 18 located near the termination of the rigid intermediate portion 16. The outer end portion of this strap—constituting a movable bracket arm 19 corresponding to the bill of a hook—is extended a suitable distance upwardly for manipulation to press it inwardly close to the shank, and the extreme distal portion is formed with a series of closely spaced transverse press-outs 20 forming ribs substantially sawtoothed in shape, with sloping parts to the upper side, as shown in Fig. 1. The parts 16, 18 and 19 may be termed a yoke, since they function to yoke an insulator and conductor supported in the device. The 30 extremity of the strap extends upwardly to a height closely adjacent to the termination of the circular upper part 15 of the shank.

A latch and operating means 21 is provided for compressing the arm or bill part 19 and securing it in line-locking position. It comprises principally a hand-operated lever 22 pivoted on the shank and having a bail link 23 pivoted thereon at the side of the shank opposite the arm 19 and extending toward and past the shank to the opposite side of the device so as to embrace the arm 19 at times or to swing clear thereof. The lever 22 as shown is adapted to be formed of sheet metal bent into a U-shape in cross section, with parallel semi-circular cheeks 24 extended beside the hanger and pivoted to the upper part of the intermediate shank 16 by means of a pin 25 extended through the shank on its major transverse axis. The cheeks are extended downwardly and reduced in extent so as to form a tapered operating arm 26 of lever 22, which in locking position extends to near the lower end of the intermediate shank portion 16 and is turned outwardly and formed with a rolled end 27 constituting a finger piece by which the initial movement of the lever from locking position may be effected. It will be noted that in the locking position of the lever as shown in Fig. 1, the extremity of the lever 22 is the lowermost part of the device and projects at 27 below the bight 18 so as to be easily struck and operated by the end of a pike swept beneath the device by a lineman on the ground. The bail 23 extends from an intermediate tooth 20 to its connection with the lever on a line which is below the pivot pin 25—that is, beyond dead center relation of the bail and pin 25 so that the tendency of the arm 19 to spring outwardly in opposition to confinement by the bail, will hold the lever 22 in locked position so that it cannot be too easily released.

This dead center locking function may be accomplished by other mechanical forms, and for that reason the parts 26, 23, and 19 together may be termed a toggle device.

The cheeks 24 are so extended from the direction of the arm 26 that they function with the arm as the short arm of a bell crank lever, the bail being pivoted at the heel of the lever and the lever fulcrumed at the end of the short arm. This short arm is of such length that when the lever 22 is swung to its uppermost position as dotted at *a*, in Fig. 1, the pivot of the bail on the lever is located beside the upper shank 15, and the bail is easily movable beyond the extremity of the arm 19 of the insulator yoke to either engage the latter or release it. With the lever in the last named released position, the bail may be pressed downwardly so as to slide over and against the teeth 20 to a position such as shown at *a* or lower, at the right hand side of Fig. 1. Then the lever 22 may be pressed downwardly to locking position as shown in full lines in Fig. 1, thereby drawing the arm 19 inwardly toward the shank to wire-locking position shown in full lines and swinging the bail link beyond dead center relation between the lever 22 and arm 19 so that the parts are retained in locking position.

The cheek 24, at one side or at each side, is extended upwardly and formed with a curved corrugated edge portion 28, engaged frictionally against the side of the bail, so that when the bail is swung upwardly as at *b* in Fig. 1, it will be retained in such raised position by pressure of its arm or arms into the corrugations. Thereafter, upon downward movement of the lever 22 the bail will be raised by the corrugations and caused to swing upwardly until it rests against the upper shank as at *c* in Fig. 1, the weight of the lever then retaining the bail in raised position so that it will not interfere with emplacement of a conductor in the insulator, or its removal.

It may be noted that in releasing movement of the lever 22 from the position shown in full lines in Fig. 1, a portion of the corrugations 28 will pass wipingly within the bail, while the latter is positioned as at *a* in Fig. 1, and thereafter lowering of the lever will raise the bail nearly to the position shown at *c*, so that release of the arm 19 may be effected by a single operation, consisting in the swinging of the lever 22 to its raised position, and lowering it substantially to the dotted position shown at *c* in Fig. 1.

At the outer end of the series of corrugations 28, a stop lug 29 is formed on the edge of the cheek 24, so that when the bail 23 is raised to its full useful limit, it is stopped by the lug 29. The bail is thus retained always within a limited range of movement convenient for lowering to engagement with the strap arm 19 of the yoke when required, and preventing movement of the lever 22 excessively beyond releasing position.

Snugly fitted in the bight 18 of the bracket or yoke there is a split or channelled sleeve member 30 of elastic deformable rubber-like insulating material, this sleeve being substantially circular in cross section, except at a slot or channel 31, extending through its length and having a bottom part located centrally in the sleeve 30 and substantially concentric with the sleeve. It should be noted that the slot 31 is shaped and formed at its entrance through the periphery of the sleeve with a width which is just sufficient to admit the conductor 32, when the strap arm 19 is free from the bail 23, at which time the slot 31 is presented toward the open space between the arm 19 and the body of the shank thereadjacent. When the arm 19 is drawn in by the bail, the pressure on opposite sides of the sleeve 30 causes the material at the sides of the slot 31 to move inwardly over the conductor laid therein and confine the latter at the lower part of the slot, substantially concentric with the sleeve 30, preventing loose movement of the conductor in the insulator and obviating liability of the conductor becoming casually displaced from the insulation into contact with the shank 16 or arm 19.

The insulator sleeve may be formed of a single body of suitable elastic quality, but preferably it includes a harder outer layer 33 which will tend to confine the inner softer portion. The inner part has been made of sponge

rubber, and the outer part of polyethylene. However, the inner part may be of a quality similar to automobile tire tube or tread rubber, and the outer part 33 may be of a shell-like quality so that its extremities adjacent the slot 31 will press the softer material inward when the yoke is closed, so that retention of the conductor 32 will be more secure.

In Figures 4 and 5, the upper end of the shank has been adapted for hook-on engagement with a cross arm, the blank being lengthened and formed as a hook 35, with a right angle bight 36 and a bill arm 37 nearly or quite parallel to the upper shank part 11-a. The extremity of the bill arm is formed with a slightly outturned part 38, and a returned diagonal spur 39 on the inner side of the arm, projecting toward the shank. The side of this returned part and spur toward the shank presents an inclined edge 40, one end of which is at the extremity of the outturned part 38. The latter end of the edge 40 is spaced from the shank 15-a slightly more than the horizontal transverse dimension of the cross arm. A number of upwardly directed spurs 41 may be formed on the inner side of the shank opposite the arm 37. The lower part of the shank, and the strap portion, are shaped as first described, and the bail and locking lever assembled thereon also constructed as in the first instance.

In the use of this form of the shank, the opening of the hook 35 is presented downwardly over the cross arm with the sloping edge 40 resting against the junction of the top and side of the cross arm and the shank 11-a resting against the opposite side of the cross arm. A strong downward pull is then applied to the shank manually if accessible, to pull the hook down to slide the spur 39 downward beside the cross arm (the inclined face 40 sliding against the side of the cross arm and pressing the bill arm outwardly to permit this movement), and the shank 11-a pulled or pressed into vertical position against the side of the cross arm opposite the bill of the hook.

Or, after initial positioning of the hook over the arm, a hammer 34 may be used to drive the hook downward into proper engagement and fit on the cross arm, by blows delivered on the upper side of the bight and shank of the hanger. One or more final blows may be delivered against the outer side of the part 33 to drive the spur 39 into the cross arm. The spurs 41 will prevent rising of the hanger on the cross arm, and the spur 39 will effect permanent fastening to the cross arm. Removal may be effected by pressing the bill arm 37 outward to disengage the spur 39.

After emplacement of my insulator by any form of cross arm attachment, the locking device may be operated from the ground by means of a hand pole, or preferably a device like a fireman's pike, and after movement of the lever 22 from locking position to position *c*, the wire conductor 32—previously laid along the ground beside the line of poles—may be lifted by the pole or pike and laid in the insulator sleeve 30, after which the pole or pike is used to draw the bail 23 downward over the free end 19 of the strap, and the lever 22 then pulled down to locking position, completing securement of the conductor. Before placing the wire in the insulators of a new line, the line should be deadended as customary, and then the wire lifted to place in the insulators as indicated. Before closing the insulators on the wire, the line should be properly or approximately sagged in conformity with standard practice although in emergency the requirements of necessity may involve departures from ideal practice.

By forming the insulator 30 of suitable length, and with the slot 31 properly proportioned to the size of wire, the insulator 30 will act as a vibration dampener, minimize wear and other destructive effect on the insulator, and hold the line against slippage.

Although the invention has utility for emergency stringing of lines, and rapidly extending military communications, it also has utility for more or less permanent installations generally in place of upstanding pins with cap

insulators, which usually require the presence of a line-man on the pole to install a line on the insulators and secure it. In the form illustrated this invention obviates need for running the line over the cross arm, and when used on the lowermost cross arm of a number, or on a pole with a single cross arm, the wire may be lifted to place as described without likelihood of interference with wires already strung either on standard pin insulators or on under arm insulators; without requiring a line-man on the pole, and with great saving of time over conventional practice. Replacement of wires on upper cross arms of a number on the same pole may also be effected with as much facility as with standard pin insulators.

In the setting up of a line with my invention, if no established line of poles and cross arms is in place and available, poles with cross arms bored and having my hangers set thereon, may be erected, and the wire thereafter laid along the ground and lifted and secured as before described.

It should be noted that by extending the saddle insulator 30-33 horizontally at each end a distance beyond the yoke as indicated in Fig. 3, short-radius flexing of the conductor near the insulator, incident to sway by wind and by other forms of vibration, will be distributed longitudinally of the conductor, so that liability of fatigue of the metal of the conductor by these causes will be greatly minimized, with lessened occurrences of failure due to such causes. Ice load in sleet storms is prone to cause breakage near conventional insulators due to fatigue.

The invention is of great value in the establishment of new lines, especially where metal poles and cross arms are employed, contributing to the rapidity of the work and obviating need for a large part of the manual work to be performed in the field. In such case, to set up a line of communication in virgin areas, the poles and cross arms, with braces and with my hangers set in the same kind of holes heretofore employed for metal insulator pins, are shipped to the right-of-way or route; and pole-erection crews set up the poles by conventional procedure, the insulator yokes being kept closed during transportation, although they may be opened as the poles are erected, and left open, ready for the stringing of the wire. Thereafter, the procedure above described for emplacement and sagging of the line is carried out, completing the establishment of the field line. In this way, it is never necessary for men to climb the poles when engaged in line laying or wire removal.

It is of especial advantage in the use of my invention that the lever arm 26 is operable by a push in one direction to close and lock the insulator in engagement with a line wire, and a push in the opposite direction to effect its release, and as this movement involves a movement between two positions at limits which must be at opposite sides of the dead center referred to above, the lever and linkage may be termed a full-stroke device. Both movements of the lever may be readily accomplished by a push or pressure of the end of a pole in respective directions against the lever at 27.

While the invention has been presented as a suspension insulator, it may be otherwise mounted when found desirable, and the shank suitably shaped, or other mounting provided by which the conductor may be supported above or beside a cross arm or other carrying body.

Various modifications in the construction and arrangement of elements in the device will be permissible without departing from the spirit of the invention as herein-after claimed, and many such modifications will suggest themselves to those versed in the art to adapt the device to special situations.

I claim:

1. An electric line wire support for mounting on a cross arm, and constructed with a pendant line securing part arranged so as to hang below an engaged cross arm,

- said pendant part consisting of a substantially U-shaped resilient bracket body having relatively movable extremities initially spaced apart from a perpendicular line therebetween so as to form a clear opening from within the bracket at its upper part, whereby a horizontal wire may be moved thereinto by translation substantially vertically, an elastic, horizontally elongated deformable rubber-like insulator fitted to the bight of the bracket and having an opening longitudinally thereof on the upper side of the insulator in the direction of the opening in said bracket said opening in the insulator being of a size to receive snugly a line wire to be supported, and holding means on the bracket movable to compress the sides thereof toward each other a distance, including toggle means to secure said holding means releasably in bracket-compressing position and including a full stroke operating member, having a horizontally movable extremity projecting below all other parts of the device for press operation by a pole-like tool when swung horizontally beneath the U-shaped bracket.
2. The structure of claim 1 in which one arm of said bracket is a rigid shank and the other relatively movable, a line locking and release arm lever pivoted on said shank a distance from the bight of the U-shaped part, a bail pivoted on the lever having a transverse part to embrace the said movable arm of the bracket, said bail being inwardly of the pivot of the lever toward said bight when the lever is in line-locking position, and said bail being of a length to hold the outer end of said relatively movable arm of the bracket compressed to a minimum spaced relation to the shank in line-locking position of the lever.
3. A wire-clamping insulator device comprising a body member substantially U-shaped, a resilient deformable rubber-like elongated member set transversely in the bight of the U-shaped member and having a longitudinal channel therein open toward the open part of the U-shaped member, a conductor-securing bell crank lever fulcrum-pivoted on a main arm of the bracket, the lever having an operating arm arranged to lie beside the said main arm when in conductor-securing position, a bail pivoted on the lever eccentrically of the fulcrum pivot of the latter and having a bight arranged to embrace and draw the free end of the U-shaped clamping member toward clamping position when said operating arm is moved toward said main arm, at least one cheek member on the lever extended beside the bail and having tooth-like members thereon to engage successively and wipingly against the bail as the lever and bail are moved relatively in their pivotal relation, whereby the bail will be held yieldingly in alternative inoperative positions when free of the opposed arm of the bracket.
4. The structure of claim 3 wherein the lever is a bell crank and has one arm pivoted at its extremity on the bracket, and a heel portion pivoted to the bail, and having at least one cheek portion extended from said one arm within the bail, said cheek having an outer curved portion corrugated to wipingly engage against the side of the bail to hold the latter and the lever yieldingly at various positions in their relative pivotal movement.
5. The structure of claim 4 in which a stop lug is formed on said cheek at one predetermined limit of relative movement of the lever and bail, to stop relative movement of the bail in that direction.
